UNITED STATES PATENT OFFICE.

JOHN K. OSTRANDER, OF NEW YORK, N. Y.

PENDULUM HIGH-VOLTAGE AIR-BREAK SWITCH

1,414,892.

Specification of Letters Patent. Patented May 2, 1922.

Application filed December 31, 1919. Serial No. 348,514.

To all whom it may concern:

Be it known that I, JOHN K. OSTRANDER, a citizen of the United States, and resident of the city of New York, New Brighton, 5 borough of Richmond, in the county of Richmond and State of New York, have invented a new and Improved Pendulum High-Voltage Air-Break Switch, of which the following is a full, clear, and exact description.

10 This invention relates generally to a new and improved high potential electric switch, and more particularly to a switch of the above character adapted more particularly for use in air only.

15 In switches heretofore provided, it has been difficult to obtain a suitable air break switch which will permit an air gap of suitable length to be formed between the contacts of the switch, and further it has been 20 difficult to obtain a construction and arrangement of switch parts so that upon breaking, the arc formed would not seriously burn the contacts. In order to overcome the latter, horns and other complicated constructions have been used.

25 One of the objects of this invention is to provide a high voltage air-break switch having its parts constructed and arranged to overcome the difficulties above noted, and 30 which will permit a high voltage circuit carrying a large amount of power to be interrupted in air quickly and safely by gravity action through a pendulum construction.

35 A further object of this invention is to provide an improved switch constructed so that the contacts thereof are normally protected from the weather elements, such as rain, sleet and snow, the arrangement being 40 such that in breaking, any arc formed is carried away from the main contacts.

45 A further object of this invention is to provide a pendulum switch in combination with a manually operable or an automatic tripping mechanism, the parts being so arranged that the opening of the switch is effected by gravity without the application of external force, so that the contacts are normally in an open position, when the 50 switch parts are in the position of stable equilibrium.

A further object of this invention is to provide a high voltage switch construction so arranged that the insulation may be con-

veniently mounted, and the terminals may 55 be secured to the arms at a relatively stationary point thereof, thus minimizing the possibility of an open circuit caused by a severed connection, which oft times is caused by a moving conductor. A further object of this 60 invention is to provide a high potential switch construction and a tripping mechanism therefor, which may be conveniently manually operable from a distant point.

A further object of this invention is to 65 provide in a high potential air-break switch of the pendulum type, a means for dampening a swinging to and fro movement of the parts. A switch constructed in accordance 70 with this invention, is particularly adapted for use on high potential polyphase alternating current circuits, but it is understood that it is not limited thereto. One of the important features of a switch constructed in accordance with the invention is the provision of a pendulum construction embodying 75 a support, and an arm having one end pivotally connected to the support, a carrier bar suitably connected to the other end of the arm and extending laterally thereof, and a 80 switch arm connected to the said carrier bar at one end through a suitable insulator, suitable contacts being located at the other end, the said switch arm being arranged to move in a plane offset from the plane of movement 85 of the pivoted arm, the switch arm preferably being arranged to extend from the carrier bar in radial alignment with the pivoted arm so that a point on the contact arm will be in substantial alignment with the point of 90 pivotal support, such a point being substantially stationary, and presenting a desirable point of connection for the line, cable or conductor.

95 Other objects and advantages will be apparent from the following description, the accompanying drawings illustrating for example one practicable embodiment of the invention, and the appended claims. The invention consists in the construction arrangement and combination of parts hereinafter more fully described, a practical embodiment of which is shown in the accompanying drawings forming a part of the specification, in which similar characters of reference 100 designate corresponding parts in the several views.

105 Figure 1 is a top plan view of a three pole

switch with the contacts of the outside arms shown in a closed position.

Figure 2 is a side elevation view of Figure 1, with certain parts shown broken 5 away.

Figure 3 is an elevation view looking in the direction of the arrows and taken generally on the line 3—3 of Figure 1.

Figure 4 is an enlarged detail sectional 10 view of part of the tripping mechanism.

Figure 5 is a view of Figure 4 in side elevation.

Figure 6 is a sectional view, showing certain parts broken away, looking in the direction of the arrows and taken on the line 15 6—6 of Figure 4.

Figure 7 is a sectional view of the contacts and arm looking in the direction of the arrows and taken on the line 7—7 of Figure 8.

Figure 8 is an enlarged fragmentary elevation view showing the upper part of the arms, and the contacts.

Figure 9 is a fragmentary elevation view with certain parts in section, showing in full 25 line, a portion of the tripping mechanism before being tripped, the dot and dash line position showing the position of the link toggle arrangement immediately after the toggle has been broken by the tripping bar.

Figure 10 is an enlarged broken elevation 30 view partly in section of certain parts of the tripping mechanism, showing in dot and dash line the position of the parts when the contacts are separated.

With reference more particularly to the accompanying drawings showing one practical embodiment of the invention, a three pole switch, adapted for use for example on a three phase system is illustrated. With 40 reference to Figures 1, 2 and 3, the switch comprises two pairs of arms 1—2 and 3—4 respectively, the former arms 1—2 being pivotally connected at opposite ends thereof in any suitable manner at spaced points 45 9—10 on a suitable support 5, the other arms 3—4 being similarly pivotally connected to another support 6. The carrier bars 7—8 are provided, and are preferably rigidly connected in any suitable manner

50 to one end of the arms 1—3 and 2—4 respectively, so that the said carrier bars extend laterally of the respective pivoted arms, and are permitted to rotate about the respective points of pivotal support. The carrier bars 55 7—8 as thus suspended, are substantially parallel. Suitable contact arms 11, 12 and 13 are preferably rigidly connected to the carrier bar 7 by suitable connections 14, 15, and 16 at spaced points in planes laterally 60 offset from the pivoted arms 1—3, the said arms 11—12 and 13 being preferably in parallel relation with the pivoted arms 1—2. If desired, the connectors 14, 15 and 16 may be of a type permitting angular adjustment 65 of the arms about the axis of the carrier

bar, as may also be the connectors 17 and 18 rigidly connecting the end of the arms 1—3 to the carrier bar 7. The arms 11, 12 and 13 may be insulated from the carrier bar 7 by suitable insulators 19, 20 and 21, which in-

70 insulators are preferably arranged at one end of the respective contact arms, between one end of the respective contact arms and a point of the contact arms corresponding to the point of pivotal support for the pivoted arms 1—3.

Such an arrangement forms a pendulum suspension construction for the contact arms, so that when moved, the contact arms rotate about a pivotal point between the ends of the arm, but out of physi-

cal contact therewith. The points of the arms corresponding to the points of pivotal support for the arms 1 and 3, are practically 80 stationary when the contact arms rotate, and thus afford desirable points at which to connect conductors 22, 23 and 24, thus minimizing the possibilities of the conductors be-

coming severed or broken which would otherwise be likely to happen if the conductors were movable. Other contact arms 25, 90

26 and 27 are similarly rigidly connected to the carrier bar 8 by connectors 28, 29 and 30 through insulators 31, 32 and 33, the said arms having contacts 34, 35 and 36 at one

end thereof adapted to engage contacts 37, 95 38 and 39 carried at one end of the arms 11, 12 and 13 respectively. It is thus seen that the respective coacting contact arms rotate in offset parallel planes from the plane of

rotation of the pivoted arms. Such an ar- 100

angement and construction enables a switch to be formed which is particularly desirable for use as a high voltage air-break switch, in that the co-acting contact arms having an independent pendulum support, may be of 105

any suitable length, and the points of the pivotal support may be suitably spaced in order to afford a relatively great distance

between the portion of the coacting contacts when closed, and of the contacts when the 110 switch is opened, thus providing a gap of proper length to insure the breaking of any arc which may form. A further advantage

of such a construction is that the contact arm is readily and conveniently insulated. 115

Still a further advantage of the pendulum construction is that when the coacting contact of the contact arms are in engagement, the switch parts assume a position of un-

stable equilibrium, so that the switch may 120 be opened by gravity action independent of other force, so that the switch normally tends to remain in an open position, thus eliminating the possibility of a switch ac-

cidentally assuming a closed position.

In use, the high voltage air switches are usually mounted at a safe distance above the ground. In Figures 1 and 2, the sup-

ports 5 and 6 are held in an elevated position on beams or channels 40 suitably sup-

125

130

ported on columns or posts 41—42, but it is to be understood that any suitable supporting means may be provided. Attention is directed to the feature of the switch construction in which the point of pivotal support for the arms 1—2 and 3—4 is from the under side of the supporting channels 5—6. Such a construction forms a protection for the point of pivotal support from the 10 weather elements. It is to be understood that while two pair of pivotally supported arms have been shown herein for a three pole switch, that the invention is not limited thereto, but any suitable number of pivotal 15 supporting arms may be provided depending upon the character of the switch to be used. It is further to be understood that this invention is not to be limited to certain details of construction shown herein, but 20 that the same may be varied to suit individual preference and conditions of use.

Referring more particularly to Figures 3—7 and 8, the contact arms are shown as comprising T angle bars 43, the conductivity 25 of the arm being increased by the provision of preferably a copper bar conductor 44 suitably secured to the T arm. The ends of the respective arms are bent slightly at an angle, a blade contact 37 being fixed to one 30 end of a coacting arm, the contact construction 34 fixed to the end of the other coacting arm, being such as will normally protect the engaged contacts from the weather elements such as ice, sleet and the like, the construction 35 further being such as will prevent any arc formed upon separation of the contacts from burning the main contacts. One construction is shown in Figures 7 and 8, in which the contact blade 37 fixed to one of 40 the arms 11, is provided at its end with two conductors 45—46 having one end thereof fixed to the end of the contact blade 37, the other portion of the conductors being slightly bent to form a spring V contact. The co- 45 acting contact 34 fixed to the other arm, is formed of a conductor bent to form a V of suitable shape to slidably receive the spring conductors 45—46 at the end of the contact blade 37. As a means of limiting the outward 50 movement of the sides 47—48 of the contact 34, forming the V, spaced bolts 49 and 50 are provided, a link 51 being used to separate or hold one end of the bolt in spaced relation. As a means of protecting the 55 engaged contact surfaces from the weather elements, a covering or top 52 extends over the contact 34. The top 52 serves as a means for holding the upper end of the bolts 49 and 50 in spaced relation. As a means of preventing the arc from burning the main contacts upon separation, the cover 52 is extended and bent to form a supplementary spring contact 53, which normally contacts with the contact blade 37 when the switch is 60 closed, and which remains in contact with

the blade 37 after the conductors 45—46 fixed to the blade are out of contact with the sides 47—48 of the contact 34, so that an arc will not be formed between the sides 47 and 48 of the contact 34 when the conductors 45 and 46 are disengaged therefrom but will be carried over to the supplementary contact 53, and the arc there formed upon disengagement from the contact blade 37. If desired, the extreme end of the supplementary spring contact 53 will be detachable, so that if such part becomes badly burned it may be readily replaced.

It is to be noted that one of the important features of a switch constructed in this manner is that any possible arc formed between the contacts is situated at a safe distance from the other switch parts, so that the danger of the main switch parts becoming burned is greatly minimized.

In order to hold the contacts in engaged position, and to control the movement of the contact arms from a distance, manually, or by automatic means, a suitable holding and tripping mechanism is provided. In the form shown, a plurality of rods 54 and 55 are provided, one end of the said rods being pivotally connected in a suitable manner to the carrier bars 7—8 respectively, the other ends of said rods being pivotally connected to a vertically movable link member 56. In operation, it may be desirable that the switch arms move in unison. In order to facilitate such a movement, a weighted member 57 may be connected through suitable flexible cables 58—59, guided over pulleys 60 and 61 to the carrier bars 7—8 respectively. In order to prevent an oscillating movement of the pendulum supported arms on opening, suitable friction washers 62—63 may be provided.

In the use of high potential switches, it is desirable to have the same so arranged that the switch may be controlled from a distance to either open or close the same. In order to effect this result, a suitable tripping mechanism is shown suspended from the channels 40 by a support 64. The tripping mechanism is supported in any suitable casing 65. The closing of the switch is effected by moving the link member 56. For this purpose, a plunger 66 having notches 67 is connected to the link 56, and is adapted to be guided at one limit of travel within apertures formed in the casing 65. The plunger is held in upper locked position, as shown in Figure 4, by links 68—69 having slots 70 and 71, one end of said links engaging the notches 67 of the plunger, the other end of said links 68 and 69 being pivotally connected to one end of the yokes 72 and 73 respectively, the other end of said yokes being pivotally connected by links 74, forming a toggle joint connection. The fixed point of support for the link and yoke construction, is upon the

bearing rods 75—76, extending through the slots 70 and 71 respectively. The plunger 66 is provided with an aperture 77 extending axially therethrough, and through which a 5 cable cord or other means 78 extends, one end of the cable being connected with a trip cone 79 having a flange 80 thereon, the other end of the cable extending over a suitable guide pulley 78' to a desired point from 10 which it is desired to control the switch. Preferably, the link member 56 is provided with a cone shaped aperture to correspond with the shape of the trip cone 79. In order to break the toggle joint connection 15 formed by the yokes 72 and 73 connected by the links 74, the trip bars 81—82 are slidably supported by suitable brackets 83—84 in the casing 65. Stops 85—86 are secured to the trip rods to limit the down- 20 ward movement thereof. The trip rods are arranged below the links 74, so that by thrusting the tripping bars upward, the toggle connection will be broken, and will move from the full line position indicated in 25 Figure 9, to the dot and dash line position there indicated. When in the latter position, the ends of the links 68—69 will be disengaged from the notches 67 of the plunger, and permit the switch to be opened by gravity 30 action. If it is desired to open the switch by manual operation, the cable 78 may be pulled, which will move the tripping cone 79 upward, until the shoulder 80 engages the bottom ends of the trip bars 81 and 82. 35 When these trip bars move upwardly they contact with the links 74 and break the straight line of the toggle joint which, by the impact of these links, is moved temporarily to the dotted position shown in Fig. 40 9. For a moment then the ends of the links 68 and 69 are removed from the notches 67, whereby the plunger 66 and its attached mechanism drops by gravity. However, the weight of the yokes 72 and 73 and the links 45 74 is such as to tend to restore the toggle mechanism to the dotted position shown in Fig. 10, in which the ends of the links 68 and 69 ride along the normal surface of the plunger 66. However, when the plunger 50 is in its lowest position, the toggle members are in the full line position shown in either Fig. 9 or Fig. 10, since the upper end of the plunger 66 is below the ends of the links 68 and 69. Therefore, when the plunger is 55 pulled upwardly to close the switch, the wedge or tapered end of the plunger 66 forcibly hits the ends of the links 68 and 69 and for an instant moves them up to the dotted position shown in Fig. 10, until the 60 notches 67 come in alignment with the ends of the links 68 and 69 which, thereupon, immediately drop into place. The dotted positions shown in Figs. 9 and 10 are only temporary. It is understood that when it is 65 desired to close the switch the cone 79 may

be moved up very gently so as not to force the bars 81 and 82 up hard enough or far enough to contact with the link 74 but merely raises the member 56 and the plunger 66 with their co-operating parts until they 70 engage as immediately above mentioned. The cable 78 is then suddenly pulled, which movement will forcibly project the trip bars upward in contact with the links 74, and breaking the toggle connection in a manner 75 above stated. If it is desired to actuate the trip mechanism automatically, an electroresponsive device 87 may be provided to break the toggle. In the form shown, a projecting arm 88 is connected to and extends outward from one of the yokes 72, so that through a suitable mechanism as for instance a bell crank having arms 89 and 90, the trip mechanism may be released. In the form shown, one of the arms of the bell crank 80 89 is pivoted intermediate the ends, one of the ends extending beyond the point of pivotal support and arranged to be actuated by the core 91 of the electroresponsive device 87 when energized. The electroresponsive 90 device may be arranged in any manner well known in the art either to be operable upon increase of current or voltage, or may be independently controlled through suitable switches. It is to be understood however 95 that any suitable arrangement may be provided for automatically breaking the toggle connection.

In order to close the switch, from a position indicated in dot and dash lines of Figure 3, the cable 78 is pulled until the trip cone 79 engages the link 56, after which continued force is exerted upon the cable until the plunger is moved to its uppermost position, where the lower ends of the links 68 100 and 69 will engage the notches 67 of the plunger. There is shown in dot and dash position in Figure 10, the position of the links and toggle connection after the plunger has been forced between the ends of the 105 links 68—69 but before the ends of the links have been seated in the notches 67. The full line position shows the position of the links and toggle connection after the ends of the links have been seated in the notches. It is 110 to be noted that the slots 70 and 71 in the links 68 and 69 permit the proper movement of the links on the rods 75—76.

It is to be noted that in a gravity actuated pendulum switch of this construction, a construction is afforded by which a high potential heavy duty switch may readily be constructed, giving a wide air-break and forming a rugged and simple construction having its parts protected from the weather 115 elements, and this is obtained without the use of many parts of complicated construction.

While but one practical embodiment of the invention has herein been shown, it is to be understood that various changes and modi- 120 125 130

fications have been made without departing from the spirit and scope of this invention.

Having thus described my invention, what I claim as new and desire to secure by Letters Patent, is:

1. A high potential air-break switch including a support, a supporting arm pivotally connected to said support, a switch member carrier bar connected to said arm and extending transversely thereof at a point spaced from the point of pivotal support, a contact arm connected to said carrier bar at a point offset from said arm.
2. A high potential switch including a support, a supporting arm pivotally connected to said support, a switch member carrier bar extending laterally of the arm and connected thereto, the said bar being adapted to move about the point of pivotal support, a contact arm connected to the carrier bar in a plane offset from the said first named arm, a contact at one end of said contact arm, and an insulator between said contact and the point of connection with the carrier bar.
3. A high potential switch including a support, a supporting arm pivotally connected at one end thereof to said support, a contact arm offset from said pivoted arm, and connections between the free end of the pivoted arm and one end of said contact arm whereby said contact arm is aligned with respect to said pivoted arm but offset therefrom.
4. A high potential air-break switch comprising a contact arm adapted to rotate around an axis, a pivotally supported arm adapted to rotate around the axis in a plane offset from the plane of rotation of said contact arm, said contact arm being unconnected with said axis.
5. A high potential air-break switch including a plurality of arms pivotally supported at spaced points, a plurality of contact arms offset from said pivoted arms and having contacts adapted to engage each other when the switch is closed, and means rigidly connecting the free ends of the pivoted arms with one end of the respective contact arms, the said means being arranged to bring the pivoted arm and the contact arm in radial alignment, and to permit the said contact arms and pivoted arm to revolve in different planes.
6. A high potential switch comprising a pivoted arm, a contact arm spaced from and parallel with said pivoted arm, and means connecting said contact arm and said pivoted arm, the said means being connected with the pivoted arm at a point spaced from the point of pivotal connection.
7. A switch comprising a support, an arm pivotally connected at one end with said support, a contact arm spaced from and extending parallel to said pivoted arm, a contact at one end of said contact arm, an insulator at the other end of said arm, and means rigidly connecting the insulated end of said contact arm, with the other end of said pivoted arm, whereby the respective arms rotate in different spaced substantially parallel planes.
8. A high potential switch comprising a plurality of independent pivoted arms, the points of pivotal support for said arms being spaced from each other, a plurality of carrier bars rigidly connected to the free ends and extending laterally of said arms respectively, a plurality of insulated contact arms rigidly connected to the respective carrier bars and arranged to permit rotation in a plane offset from the plane of rotation of said pivoted arms, and co-operating contacts carried by said contact arms.
9. A high potential switch comprising a plurality of independent pivoted arms, the points of pivotal support for said arms being spaced from each other, a plurality of carrier bars rigidly connected to the free ends and extending laterally of said arms respectively, a plurality of insulated contact arms rigidly connected to the respective carrier bars and arranged to permit rotation in a plane offset from the plane of rotation of said pivoted arms, co-operating contacts carried by said contact arms, and pivotal means connected with said carrier bars for holding the said contacts in engagement, and retaining the said pivoted arms and contact arms in a position of unstable equilibrium.
10. A high potential switch comprising a plurality of independent pivoted arms, the points of pivotal support for said arms being spaced from each other, a plurality of carrier bars rigidly connected to the free ends and extending laterally of said arms respectively, a plurality of insulated contact arms rigidly connected to the respective carrier bars and arranged to permit rotation in a plane offset from the plane of rotation of said pivoted arms, co-operating contacts carried by said contact arms, pivotal means connected with said carrier bars for holding the said contacts in engagement, and retaining the said pivoted arms and contact arms in a position of unstable equilibrium, and a tripping mechanism associated with the pivotal means.
11. A high voltage pendulum switch comprising a support, a plurality of arms pivotally suspended from said support at spaced points to permit rotation in parallel planes, laterally extending carrier bars connected to the free ends of said pivoted arms, insulated contact arms rigidly connected to said carrier bars in a plane offset from said pivoted arms, the said contact arms being substantially parallel with said pivoted arms, co-operating contacts carried by the respective contact arms, and a tripping mechanism associated with the pivotal suspended switch arms for holding the contacts

in engagement when the switch arms and pivoted arms occupy a position of unstable equilibrium.

12. A high voltage pendulum switch comprising a support, a plurality of arms pivotally suspended from said support at spaced points to permit rotation in parallel planes, laterally extending carrier bars connected to the free ends of said pivoted arms, insulated contact arms rigidly connected to said carrier bars in a plane offset from said pivoted arms, the said contact arms being substantially parallel with said pivoted arms, co-operating contacts carried by the respective contact arms, a tripping mechanism associated with the pivotal suspended switch arms for holding the contacts in engagement when the switch arms and pivoted arms occupy a position of unstable equilibrium, the said tripping mechanism including in combination a plurality of members, one end of each member having a pivotal connection with the respective carrier bars, another member pivotally connecting the other end of said members, and a tripping device engaging said last named member to maintain the contacts in engaged position.

13. A high voltage switch comprising a plurality of arms pivotally supported at spaced points to permit of rotation in parallel planes, laterally extending carrier bars rigidly connected with the free ends of the respective pivoted arms, contact arms extending substantially parallel with said pivoted arms in a plane offset therefrom, the said contact arms being insulated from and rigidly connected with the said carrier bars, co-operating contacts carried by said contact arms, the arrangement being such that when the contacts are in engagement the contact arms occupy a position of unstable equilibrium, a plurality of members having one end thereof pivotally connected to the said carrier bars, the other end of said members having a pivotal connection with a vertically movable member, and a tripping device associated with said vertically movable member for maintaining the switch parts in a position of unstable equilibrium.

14. A high voltage switch comprising a plurality of arms pivotally supported at spaced points to permit of rotation in parallel planes, laterally extending carrier bars rigidly connected with the respective pivoted arms, contact arms extending substantially parallel with said pivoted arms in a plane offset therefrom, the said contact arms being insulated from and rigidly connected with the said carrier bars, co-operating contacts carried by said contact arms, the arrangement being such that when the contacts are in engagement the contact arms occupy a position of unstable equilibrium, a plurality of members having one end thereof pivotally connected to the said carrier

bars, the other end of said members having a pivotal connection with a vertically movable member, a tripping device associated with said vertically movable member for maintaining the switch parts in a position of unstable equilibrium, the said tripping device comprising a toggle connection having means arranged to engage the vertically moving member to hold the same in a suspended position, and means for automatically breaking said toggle connection to permit the downward movement of the vertically movable member to enable contacts to separate.

15. A high potential switch comprising switch arms having co-operating contacts associated therewith, laterally extending carrier bars insulated from and rigidly connected to one end of the respective switch arms, pivotally supported arms rigidly connected to said carrier bars and extending substantially parallel with said switch arms in a plane offset therefrom whereby the said pivoted arms and switch arms rotate in spaced parallel planes, switch arms being angularly arranged and occupying a position of unstable equilibrium when the contacts are in engagement, pivotal connected members interposed between the said carrier bars for maintaining the contacts in engaged position, an electro responsive tripping device associated with said pivoted members, a gravity means having independent flexible connectors connected with the carrier bars to effect uniform movement of the switch arms upon separation of the contacts.

16. A high potential switch comprising a plurality of carrier bars, pivotally supported arms rigidly connected at their free ends with said carrier bars, the said pivoted arms being normal thereto, contact arms rigidly connected to said carrier bars in an offset parallel plane, the said contact arms being substantially parallel with said pivoted arms, contacts for said contact arms, insulators for said contact arms interposed between the carrier bar and a point of the contact arm corresponding to the point of pivotal support for the pivoted arm, and conductors connected to said contact arms at a point corresponding to the point of pivotal support for the pivoted arm, whereby the said contact arms may rotate without effecting substantial movement of the conductor.

17. The combination of switch arms, co-operating contacts therefor, one of said contacts having a bent portion having an upper covering serving to protect the main contacts from sleet and the like, the said portion being bent to form an extension whereby upon breaking the arc is carried away from the main contacts, carrier bars rigidly connected to the switch arms at one end and extending normal thereto, pivotally supported arms parallel with the switch arms and connected

to the respective carrier bars in a plane offset from the switch arms, means pivotally connecting the carrier bars for effecting pendulum movement of the switch arms, and insulators for the switch arms interposed between the carrier bars and a point of pivotal support, and a conductor connected to the switch arm at a point corresponding to the point of pivotal support, whereby the switch arm may move without producing relative movement of the conductor.

18. In a high potential air-brake switch comprising co-acting contact arms and independent pivotally supported switch arms rigidly connecting the respective contact arms forming a pendulum suspension, a pivoted means connecting one end of said switch arms for determining the position of said contact arms, and a tripping mechanism associated with said pivoted means for holding the contact arms in engaged position, the said tripping mechanism comprising a plunger connected with the pivoted means, a toggle connection having means engaging the plunger, and means for breaking the toggle to release the plunger whereby the contact arms are separated by gravity.

19. A tripping mechanism for a pendulum switch comprising a vertically movable

plunger having notches therein, a toggle connection comprising a plurality of yokes, links pivotally connecting the yokes, other links pivotally connected to the yoke at one end, the other end of said links engaging the notches of the plunger, independently fixed pivotal supports for said last named links, means arranged on the links to permit relative longitudinal movement between the support and the links, and means for breaking the toggle connection to disengage the ends of the links from the notches of the plunger.

20. A high potential switch comprising a plurality of coacting switch arms adapted to rotate in the same plane, a plurality of pivoted arms in another plane extending substantially parallel with said switch arms, carrier bars rigidly connecting said pivoted arms and said switch arms, the said switch arms being at an angle when the switch is closed, a weight, a flexible means extending from said weight and connecting said carrier bars, to effect uniform movement of said carrier bars, and friction means restraining the said carrier bars against a swinging movement.

JOHN K. OSTRANDER.
